CARBIDE INSERTED BUTTON DIE

Ronald G. Burnet, Detroit, Mich., assignor of one-fourth to Lloyd Bastian, one-fourth to Walter S. Smith, both of Detroit, Mich., and one-fourth to Robert Moore, New Hudson, Mich.

Filed June 22, 1964, Ser. No. 377,005
9 Claims. (Cl. 76—107)

The invention relates to button dies and refers more specifically to a carbide inserted button die and the method of manufacture thereof.

In the past multiple material dies have been manufactured by producing a die body and an insert separately, after which the insert has been secured to the die case by brazing or the like with the case and insert aligned as nearly as possible. The die has then been finished by lapping or jig grinding in a separate operation. The separate finishing operation is necessary since the exact locating of the insert in the die case on securing the insert to the die case is extremely difficult or impossible.

This method of producing inserted dies is particularly expensive and inefficient. Further, dies produced by this method are subject to premature failure in use due to misalignment of the insert, stresses set up in the insert during manufacture or shock in use.

It is therefore an object of the present invention to provide an improved method of producing a carbide inserted button die.

Another object is to provide a method of producing a carbide inserted button die comprising securing a carbide insert blank in a steel die case blank and finishing the die opening through the carbide insert and die case simultaneously by means of electric machining from the rear of the die case blank.

Another object is to provide a method of producing a die as set forth above wherein the carbide insert is secured to the steel die case by means of silver solder.

Another object is to provide a method of producing a carbide inserted button die wherein a copper cushioning member is positioned between the steel die case and carbide insert.

Another object is to provide improved button die structure.

Another object is to provide button die structure including a steel die case and a carbide insert silver soldered to the steel case.

Another object is to provide button die structure as set forth above and further including a cushioning member positioned between the carbide insert and steel die case.

Another object is to provide a carbide inserted button die and method of manufacture thereof which is simple, economical and efficient.

Other objects and features of the invention will become apparent as the description proceeds, especially when taken in conjunction with the accompanying drawings, illustrating a preferred embodiment of the invention, wherein:

FIGURE 1 is a diagrammatic elevation view, partly broken away, of electric discharge machining apparatus for manufacturing carbide inserted button dies in accordance with the invention.

FIGURE 2 is a longitudinal section view of a carbide inserted button die constructed in accordance with the invention.

FIGURE 3 is a cross section of the carbide inserted button die illustrated in FIGURE 2 taken substantially on the line 3—3 in FIGURE 2.

FIGURE 4 is an enlarged portion of the longitudinal section view of the carbide inserted button die illustrated

2

in FIGURE 2 illustrating in more detail the connection between the carbide insert and steel die case.

With particular reference to the figures of the drawings, one embodiment of the invention will now be considered in detail.

As best shown in FIGURE 2 the carbide inserted button die 10 includes a steel case 12 in which a carbide insert 14 has been secured by cushioning structure 16, illustrated best in FIGURE 4.

The carbide inserted button die 10 is manufactured by first producing the die case 12 and securing a carbide insert 14 thereto with the cushioning means 16 interposed therebetween. The die case 12 and carbide insert 14 are then electrically machined simultaneously from the rear to provide a finished button die by electric discharge machining apparatus 13 illustrated best in FIGURE 1.

More specifically, the carbide inserted button die 10, as shown in FIGURE 2, includes the case 12 which may be machined of air hardened tool steel or which alternatively may be formed from powdered metal by known processes. Case 12 has the opening 18 extending longitudinally therethrough which opening includes the slug relief portion 20 and the carbide insert supporting portion 22 at the opposite ends thereof.

Tear shaped locking recesses 24 are provided around the die case 12 as needed to lock the button die 10 in a predetermined position in a die by means of the usual balls 26. Balls 26 are shown in phantom for illustrative purposes only.

The carbide insert 14 is, as shown, provided with a circular opening 28 extending therethrough. It will be understood that the opening 28 through the carbide insert 14 and the opening 30 in the die case 12 may be of any desired configuration. Thus, the button die 10 in conjunction with a corresponding punch (not shown) may produce square, diamond, star, or irregularly shaped openings in material to be punched.

The cushioning structure 16, as best illustrated in FIGURE 4, includes a base copper member 32 which may be, for example, three thousandths of an inch thick, positioned in the bottom 29 of the recess formed by portion 22 of opening 18 and secured to the die case 12 by means of silver solder 34. The copper cushioning member 32 is also secured to the carbide insert 14 by silver solder 34.

Cushioning structure 16 further includes the copper cushioning member 36 secured between the axially extending walls 38 of the recess formed by the portion 22 of opening 18 and the radially outer surface 40 of the carbide insert 14 by the silver solder 34, as shown best in FIGURE 4.

The carbide inserted button die 10 is manufactured by first producing the die case 12 in blank form of air hardened tool steel or with the usual powdered metallurgy procedures to produce a steel blank having the properties of air hardened tool steel and subsequently machining the die case blank to the form illustrated in FIGURE 2. The die case 12 is then heat treated to a hardness of approximately fifty-eight Rockwell.

A carbide insert blank 14 having a rough undersized opening 28 therein is then produced separately and secured in the portion 22 of opening 18 in die case blank 12 by silver soldering the copper cushioning members 32 and 36 as required between the die case 12 and the carbide insert blank 14.

The exterior of the die case is then centerless ground to an exact outside diameter, after which the insert opening 28 and the central portion 30 of passage 18 in the die case are electrically machined simultaneously from the rear of the die case by electric discharge machining apparatus 13 to produce a finished carbide inserted button die.

Electric discharge machining apparatus, such as apparatus 13 are well known in the metal working arts. Apparatus 13 will not therefore be considered in detail herein. Briefly however the electric discharge machining head 15 holding electrode 17 is fed toward button die 10 by servo motor 19 to maintain a predetermined spark gap therebetween in accordance with the electric potential applied thereacross by the pulsating source of electric energy 21. A dielectric fluid is pumped through electrode 17 and tank 23 by pump 25 during machining.

Thus a carbide inserted button die is produced without the necessity of expensive finishing, such as lapping and jig grinding. Further the carbide inserted button die as disclosed will not be subject to early failure due to cracking of the carbide insert from stresses due to differential shrinkage of the die case 12 and insert 14 or shock due to impact in operation.

While one embodiment of the present invention has been disclosed, it will be understood that other modifications and embodiments are contemplated. It is the intention to include all such embodiments and modifications as are defined by the appended claims within the scope of the invention.

What I claim as my invention is:

1. The method of producing a carbide inserted button die comprising separately producing a die case blank and a carbide insert blank, securing the carbide insert blank in the die case blank and simultaneously electrically machining a die opening completely through the carbide insert and die case which opening has the same dimension in the die case blank and in the carbide insert blank at the inner face between the die case blank and carbide insert blank.

2. The method as set forth in claim 1 wherein the opening through the die case and insert are electrically machined from the rear thereof.

3. The method as set forth in claim 1 and further including securing a cushioning member between the carbide insert blank and die case blank prior to said machining.

4. The method of producing a carbide inserted button die comprising forming a die case blank of air hardened tool steel, machining the blank to a desired form, heat treating the blank, securing a carbide insert blank to the die case blank with cushioning means positioned therebetween by silver soldering the cushioning means to the die case blank and to the carbide insert blank, centerless grinding the outside diameter of the button die to a predetermined exact size and subsequently simultaneously

electrically machining the die opening through the die case blank and carbide insert blank.

5. A button die comprising a die case having a die opening extending axially therethrough and a recess in one end of the die case over the end of the die opening for receiving a carbide insert, a carbide insert having a die opening therein of the same dimension as the die opening in the die case positioned within the recess in the button die with the die openings aligned and means securing the carbide insert within the recess in the die case.

6. The method as set forth in claim 4 wherein the die opening through the die case blank and carbide insert blank are electrically machined from the rear thereof.

7. The method of producing a carbide inserted button die comprising forming a die case blank, machining the blank to a desired form, securing a carbide insert blank to the die case blank with cushioning means positioned therebetween by silver soldering the cushioning means to the die case blank and to the carbide insert blank, centerless grinding the outside diameter of the button die to a predetermined exact size and subsequently simultaneously electrically machining the die opening through the die case blank and carbide insert blank.

8. The method of producing a carbide inserted button die comprising forming a die case blank, machining the blank to a desired form, securing a carbide insert blank to the die case blank with cushioning means positioned therebetween, centerless grinding the outside diameter of the button die to a predetermined exact size and subsequently simultaneously electrically machining the die opening through the die case blank and carbide insert blank.

9. The method of producing a carbide inserted button die comprising forming a die case blank, machining the blank to a desired form, forming a carbide insert blank, securing the carbide insert blank to the die case blank, machining the outside of the button die to a predetermined exact size and subsequently simultaneously electrically machining the die opening through the die case blank and carbide insert blank.
